UNITED STATES PATENT OFFICE

STANLEY E. GUNNISON, OF NEW YORK, N. Y.

DESIGN FOR A COLLAPSIBLE TUBE SUPPORT

Application filed August 11, 1932. Serial No. 44,575. Term of patent 14 years.

To all whom it may concern:

Be it known that I, STANLEY E. GUNNISON, a citizen of the United States, residing at New York city, county of New York, borough of Manhattan, and State of New York, have invented a new, original, and ornamental Design for a Collapsible Tube Support, of which the following is a specification, ref-

erence being had to the accompanying drawing, forming a part thereof.

The figure of the drawing illustrates a perspective view of my new design.

I claim:

The ornamental design for a collapsible tube support as shown.

STANLEY E. GUNNISON.
